UNITED STATES PATENT OFFICE.

CHARLES D. HOWELL, OF COLUMBUS, OHIO, ASSIGNOR OF TWO-THIRDS TO MAURICE S. CONNORS AND STEWART S. STIFFEY, OF SAME PLACE.

APPARATUS FOR GENERATING ACETYLENE GAS.

SPECIFICATION forming part of Letters Patent No. 635,727, dated October 24, 1899.

Application filed July 17, 1899. Serial No. 724,076. (No model.)

To all whom it may concern:

Be it known that I, CHARLES D. HOWELL, a citizen of the United States, residing at Columbus, in the county of Franklin and State 5 of Ohio, have invented new and useful Improvements in Apparatus for Generating Acetylene Gas, of which the following is a specification.

This invention relates to apparatus for generating acetylene gas.

My invention has for its principal object to provide an acetylene-gas generator adapted more especially for use on locomotives, railway-cars, carriages, automobiles, or other vehicles. The apparatus may be placed on the vehicle in any convenient situation, and the gas may be used direct from the delivery-pipe of the machine or be conducted in pipes to a suitable storage-receptacle, whence it may be 20 taken for use as required.

The invention consists of features of construction and novel combinations of parts in an apparatus for generating gas by the reaction of water upon calcium carbide or other 25 chemical substance having an affinity for water and capable of reacting therewith to generate a gas adapted for illuminating, heating, or other purposes, as hereinafter described.

In the annexed drawings, illustrating the 30 invention, Figure 1 is a longitudinal sectional elevation of my improved acetylene-gas generator. Fig. 2 is a plan view of the apparatus. Fig. 3 is an end elevation of the same. Fig. 4 is a front elevation of the gas-generator. Fig. 5 is a cross-sectional view through the carbide-box. Fig. 6 is a detail sectional view showing the manner of attaching a cap to the end of the carbide-box. Fig. 7 is an end elevation of a drawer for the carbide-box. Fig. 8 is a side elevation of said drawer. Fig. 9 is 35 an elevation of the other end of the carbide-drawer. Fig. 10 is a sectional detail of a spring-seat on the drawer of the carbide-box. Fig. 11 is a view of a spring-frame for holding down a cloth over the carbide in the drawer of the carbide-box.

Referring to the drawings, the numeral 1 designates a cylindrical box or vessel arranged in a horizontal position to serve as a 40 gas-generator. One end of this cylindrical box is closed by a head 2, which may be per-

manently attached. The other end of said box is closed by a removable cap 3, that is internally screw-threaded to engage external screw-threads on a ring 4, surrounding one 55 end of the box or cylinder. A gasket 5 is arranged within the cap 3 in position to be pressed against by the end of the cylinder or box 1, so as to form a gas-tight joint therewith.

Within the box or cylinder 1 there is arranged a removable drawer 6 for containing the carbide or other chemical that is to be employed in the generation of gas. This drawer 6 is very nearly the same length as the box or cylinder 1, so as to nearly fill the same when placed therein. The body portion of the drawer 6 is semicylindrical or trough-shaped and is provided with a number of perforations 7, as shown. The ends of the drawer 6 consist of disks 8 and 9, to one of which is attached a handle 10 for convenience in placing the drawer within the box or cylinder 1 and for withdrawing it to recharge said drawer with carbide. Each head or disk end 75 8 and 9 of the carbide-drawer is provided with a semicircular flange 11 to assist in supporting the trough or body portion of the drawer. The drawer may be formed from sheet metal or any other suitable material. Each longitudinal side edge of the trough or body portion of the drawer is flared outwardly just above the flanges 11 to form seats 12 for a spring-frame 13, that is arranged to secure in place a piece of cloth 14, which is to be extended over the carbide after the same has been placed in the drawer. This spring-frame 13 is formed with eyes 15 at its opposite ends to fit over lugs 16, projecting inwardly from the disk ends 8 and 9, as shown in Fig. 1. 85 The drawer 6 is easily placed within or withdrawn from the cylindrical box 1 after removing the screw-cap 3 from the end of said box. On the outside of this screw-cap 3 there may be arranged a pair of lugs 17, disposed in 90 such relation to each other that any suitable lever can be engaged therewith for the purpose of unscrewing said cap or for screwing it again into place.

There is secured to the upper side of the 100 cylindrical box or casing 1 a substantially rectangular water chamber or reservoir 18,

Figs. 1, 2, 3, and 4. In the top of this water-reservoir there is a filling-orifice 19, which may be closed by any suitable cap or stop. The top of the reservoir 18 is also provided with a ventilator 20 of any suitable construction to permit the escape of any gas that may gain access to said reservoir from the gas-generator. One end of the water-reservoir 18 is provided with an exit water-pipe 21, that is curved around, as shown in Figs. 1, 2, and 3, to connect at its other end with a drip-pipe 22, which is extended longitudinally through the upper portion of the cylindrical carbid-box or gas-generator 1, as shown in Fig. 1. This water-drip pipe 22 may be provided with a longitudinally-extended series of perforations or be otherwise so arranged as to provide for an equable distribution of water over the carbid contained in the drawer 6 within the generator. At the junction of the pipes 21 and 22 there is placed a hand-valve 23, by which the operator can readily control the admission of water to the gas-generator according to the requirements for the generation of gas. The gas that is generated in the carbid-holder or cylindrical box 1 finds exit through a gas-delivery pipe 24, which is extended through the water-reservoir 18 and is preferably coiled about therein, so as to provide an extended surface for securing a proper cooling of the gas and condensation of any vapor therein before the gas is conducted to the place of use or storage, thus insuring the delivery of dry gas from the machine. To the gas-generator or cylindrical box 1 there are connected a pressure-gage 25 and a safety-valve 26, as shown in Fig. 4. A water-gage 27 may be connected with the water-reservoir 18, as shown in Figs. 3 and 4, and the lower end of this water-gage is preferably provided with a drainage-valve 28, by which to draw off the water from the reservoir 18 in case there is any liability of freezing of the contents. It will be seen by reference to Figs. 1 and 5 that the carbid-drawer 6 very nearly fills the cylindrical generator or box 1 when placed therein. The disk 8, that forms one end of the carbid-drawer, is cut away at 29, Figs. 5 and 7, to permit ready passage of the inner end portion of said drawer along the water-drip pipe 22, which is extended longitudinally in the upper part of the box 1 or outer shell of the generator. This cut-away portion or recess 29 in one end of the carbid-drawer not only provides space for the drip-pipe 22, but will coact therewith to prevent turning of the carbid-drawer in its inclosing shell or box. The manner of using this gas-generating apparatus and its operation when supplied with water and carbid will be readily understood. It will be seen that the carbid is to be placed in the drawer 6 and covered with a piece of cloth 14, as shown in Fig. 5. The spring-frame 13, Figs. 1, 5, 7, 9, and 11, is then placed in position over the cloth 14 and

in bearing contact with the spring-seat 12, Figs. 7, 9, and 10, so as to hold said cloth in place, the ends of the spring-frame 13 being engaged with the lugs 16, that project inwardly from the ends of the carbid-drawer. The carbid-drawer 6 is then inserted into one end of the cylindrical box 1, and the screw-cap 3 is then attached, as shown in Figs. 1, 2, 4, and 6, so as to form a gas-tight joint with the ends of the cylindrical box 1 and prevent any escape of gas at this point. When the generation of gas is required, water may be admitted to the generator by opening the valve 23 and will be distributed through the drip-pipe 22 onto the cloth 14, which acts as a wick to spread the water equably over the surface of the carbid and also to prevent the escape of any watery vapor. The gas that is generated passes off through the gas-delivery pipe 24, and this pipe being disposed in the form of a coil within the water-reservoir 18 will facilitate condensation of any vapor and insure the delivery of a dry gas. Any gas that may gain access to the water-reservoir, as by passing thereto through the drip-pipe 22, will find an exit through the ventilator 20 at the top of said water-reservoir.

It is intended that the operator will set the valve 23 so as to keep up a steady formation of gas sufficient to supply the burners; but if the pressure of gas should get excessive the safety-valve 26 will release the gas before the pressure becomes dangerous. The pressure-gage is provided, so the operator can see what pressure is in the generator and regulate the valve 23 accordingly. The water-gage is to show how much water is in the reservoir 18 at all times, as it is important to keep the coil of the gas-delivery pipe 24 covered with water to secure a dry gas that is best suited for illuminating purposes.

What I claim as my invention is—

1. In an acetylene-gas generator, the combination of a horizontally-arranged cylindrical carbid-box closed at one end by a removable gas-tight cap, a semicylindrical carbid-drawer provided with disk-shaped ends and arranged within the carbid-box, a cloth extended over the carbid in said drawer, a spring-frame to hold said cloth in place, a water-reservoir above the carbid-box, a water-drip pipe connected with the water-reservoir and extended through the upper part of the carbid-box, and a gas-delivery pipe extended from the carbid-box and through the water-reservoir, substantially as described.

2. In an acetylene-gas generator, the combination of a carbid-box, a removable gas-tight cap for one end of said box, a carbid-drawer removably placed within the carbid-box, a cloth to cover the carbid in said drawer, a spring-frame supported by the ends of the carbid-drawer and adapted to bear on said cloth and hold the same in place over the carbid, a water-reservoir above the carbid-box, a water-drip pipe connected with the water-reservoir and extended into the carbid-box,

a valve for said pipe, a gas-delivery pipe extended from the carbid-box into and through the water-reservoir, and a ventilator for the water-reservoir, substantially as described.

5. In an acetylene-gas generator, the combination of a cylindrical, horizontally - arranged carbid-box having a permanent head at one end and provided at its other end with a removable gas-tight cap, a semicylindrical carbid-drawer provided with disk-shaped ends, the longitudinal side edges of said drawer being provided with spring-seats, a cloth extended over the carbid in said drawer, a spring-frame supported by the ends of said 10 drawer and adapted to bear on said cloth over said spring-seats, a water-reservoir, a valved drip-pipe connected with the water-reservoir and extended into the said carbid-box, and a gas-delivery pipe extended from the carbid- 15 box and through the water-reservoir, substantially as described.

4. In an acetylene-gas generator, the combination of a cylindrical carbid-box, a semi-cylindrical carbid-drawer placed in said box 20 and provided with disk-shaped ends, a cloth extended over the carbid in said drawer, a spring-frame supported by the ends of the car- 25

bid-box in position to bear upon and hold said cloth in place, a water-reservoir, a valved water-drip pipe connected with said water- 30 reservoir and extended into the carbid-box above said carbid-drawer, and a gas-delivery pipe extended from the carbid-box into and through said water-reservoir, substantially as described.

5. In an acetylene-gas generator, the combination of a carbid-box, a gas-tight cap for one end of said box, a cloth to cover the carbid, a spring-frame adapted to bear on said cloth and hold the same in place over the car- 40 bid, a water-reservoir above the carbid-box, a valve-controlled passage through which said reservoir is adapted to communicate with the carbid-box, and a gas-delivery pipe extended from the carbid-box into and through the 45 water-reservoir, substantially as described.

In testimony whereof I have hereunto set my hand in presence of two subscribing witnesses.

CHARLES D. HOWELL.
